UNITED STATES PATENT OFFICE.

CHARLES BUSHNELL DUNN, OF ALMOND, ALABAMA.

CONCRETE-MIXING APPARATUS.

No. 888,975.

Specification of Letters Patent.

Patented May 26, 1908.

Application filed June 1, 1907. Serial No. 376,779.

To all whom it may concern:

Be it known that I, CHARLES B. DUNN, a citizen of the United States, residing at Almond, in the county of Randolph and State of Alabama, have invented a new and useful Concrete-Mixing Apparatus, of which the following is a specification.

This invention relates to concrete mixing apparatus and is more particularly designed for mixing concrete.

The object of the invention is to combine a hoisting bucket with mechanism whereby the contents of the bucket will be thoroughly mixed during the hoisting operation and a predetermined quantity of liquid commingled therewith so that upon the lowering of the bucket a thoroughly mixed product can be discharged therefrom.

A still further object is to provide valve mechanism of novel form designed to operate so as to permit a predetermined quantity of liquid contained within the bucket to become mixed with the other contents of the bucket.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a section through a mixing bucket embodying the present improvements. Fig. 2 is a perspective view of a portion of a bucket and showing the relative arrangement of one of the reservoirs within the bucket. Fig. 3 is a side elevation of the bucket and its hoisting mechanism, one corner of the bucket being removed. Fig. 4 is an enlarged section through one corner of the bucket and through the reservoir therein. Fig. 5 is an enlarged detail view of one of the partition plates designed to be secured within the bucket to form a corner reservoir. Fig. 6 is a section through the plate on line x—x, Fig. 5, the flanges of the plate being bent into position to properly rest upon the walls of the bucket. Fig. 7 is an enlarged end view of one of the valves. Fig. 8 is a detail view of a clutch connection employed in the device.

Referring to the figures by characters of reference, 1 designates a yoke having supporting brackets 2 thereon in which is journaled a shaft 3 one end of which is also jour-

naled in an arm 4 extending from one side of the yoke. Secured to the shaft 3 in any suitable manner and between the brackets 2 is a pulley 5 about which is designed to be wound a hoisting rope or cable 6. A sprocket 7 is secured to the shaft 3 and supports a chain 8 which extends under and is designed to rotate a sprocket 9. This last mentioned sprocket is secured to one end portion of a tubular shaft 10 the ends of which are within the end portions of the yoke. Secured upon this tubular shaft is a bucket 11 preferably rectangular in form and two of the corners of this bucket are preferably divided from the body portion thereof by means of triangular partitions 12 which, as shown particularly in Figs. 5 and 6, are provided with flanges 13 designed to be riveted or otherwise secured to the walls of the bucket. Preferably two of these partitions are provided at diametrically opposite corners of the bucket so that in addition to the main compartment 14 within the bucket two reservoirs such as indicated at 15 are also provided. These reservoirs have suitably closed inlets 16 whereby water or other liquid to be mixed with the contents of compartment 14 may be placed within the reservoirs. A door 17 is hinged to one face of the bucket and constitutes a closure for compartment 14. This door is held normally closed by one or more spring catches 18 and extending between these catches and that wall of the bucket to which they are fastened is a shaft 19 formed with one or more cranks 20 designed to bear against the inner faces of the catches 18. A lever 21 is secured to the shaft 19 and by pulling outward on this lever the crank or cranks 20 can be swung against the catch or catches 18 so as to pull them out of engagement with the closure 17. A spring clip 22 is preferably provided for the purpose of holding the lever in a predetermined position.

A discharge pipe 23 extends from each reservoir 15 to the tubular shaft 10 and this shaft has a series of outlet apertures 24 opening into the compartment 14. The two pipes 23 are normally closed by means of slideable pistons 25 which are rigidly connected in any suitable manner as by means of a rod 26. These pistons are hollow, the ends thereof being provided with cross strips 27 as shown in Fig. 7, the inner or adjoining cross strips of the two pistons being connected to the rod 26. Swiveled within the outer cross strip of one of the pistons is one end of a screw 28.

which extend sbeyond and engages one end of the tubular shaft 10 and has an arm 29 extending at right angles from its outer end. This arm projects through a slot 30 formed 5 within a holding finger 31 which is fastened to the yoke 1 and extends laterally therefrom.

In using the mixing device herein described the two reservoirs 15 are first filled with water or other liquid to be used in the mixture, after which the desired quantity of sand, cement, or other material is placed within the compartment 14 and the closure 17 shut and secured. It is to be understood, 10 that the normal positions of the pistons 25 are across the inner ends of the pipes 23 so that it is impossible for liquid within the reservoirs to escape therefrom and through the openings 24 in shaft 10. After the material has been placed in the bucket the 15 bucket is hoisted by means of the cable 6. This will obviously cause the pulley 5 and shaft 3 to rotate and motion will therefore be transmitted from the sprocket 7 and through the chain 8 to sprocket 9 and shaft 25 10. As the bucket is secured to this shaft said shaft and bucket will rotate together. As the screw 28 is held against rotation by arm 29 and finger 31 it is obvious that as the shaft 10 revolves the screw will be moved 20 longitudinally therein so as to withdraw the pistons from across the ends of pipes 23. This opening of the valves occurs preferably 25 upon the completion of about six revolutions of the bucket, whereupon the arm 29 moves 30 out of engagement with finger 31. Therefore as soon as the bucket has been raised to a certain height the pipes 23 will be opened and the liquid contents of the reservoirs will flow therethrough and into the shaft 10 and 35 thence through the openings 24. It will therefore be discharged upon the solid contents of the compartment 14 and mixed therewith. When the bucket is lowered the 40 pistons can then be returned to their normal 45 positions. The rotation of the bucket during the return movement will agitate the contents of the bucket and cause them to be thoroughly mixed so that when the bucket returns to the point from which it is raised 50 the same can be opened and the mixture dropped therefrom in condition for use.

It will be seen that the device is very simple, durable and efficient and constitutes a convenient means for mixing concrete and 55 at the same time conveying it to a suitable point for use. It is particularly designed for use upon derricks and the like because the parts to be mixed can be placed in the bucket at one point and can be raised and conveyed 60 to the point of use, the raising and lowering of the bucket serving to mix the contents thereof. A suitable clutch can, if desired, be placed on the sprocket 7 so that the bucket need not revolve when lowering, and enabling 65 the operator to turn the bucket when

required to discharge the mixture. As shown in Fig. 8 this clutch may consist of a ratchet wheel 32 secured to the shaft 3 and designed to be engaged by a pressed pawl 34 connected to the sprocket 7. 70

What is claimed is:

1. The combination with revoluble means adapted to engage and to be actuated by a hoisting element, and a bucket movable with said means and having a mixing chamber and a reservoir; of mechanism operated by said means for rotating the bucket, and means operated by the rotation of the bucket for establishing or closing communication between the reservoir and the mixing chamber. 80

2. The combination with revoluble means adapted to engage and to be rotated by a hoisting element, and a bucket movable with said means and having a mixing chamber and a reservoir; of mechanism operated by said means for rotating the bucket, a valve, and means operated by the rotation of the bucket for shifting the valve to open or close communication between the reservoir and the mixing chamber. 90

3. The combination with revoluble means adapted to engage and to be rotated by a hoisting element, and a bucket movable with said means and having a receiver and a mixing chamber; of mechanism for transmitting rotary motion from said means to the bucket, a valve for closing communication between the reservoir and mixing chamber, means operated by the rotation of the bucket for actuating the valve to open or close communication between the reservoir and mixing chamber, and means for distributing the discharged contents of the reservoir within the mixing chamber. 100

4. Mixing apparatus comprising a bucket, a tubular apertured shaft in said bucket having a mixing chamber and having a reservoir opening into the shaft, a valve within the shaft for closing communication between the reservoir and mixing chamber, a revoluble element supported above and movable with the bucket, a hoisting element adapted to engage and rotate said revoluble element, mechanism for transmitting rotary motion from said means to the shaft and bucket, and means operated by the rotation of the bucket for rotating the valve. 105

5. Mixing apparatus comprising a bucket having a mixing chamber, a tubular apertured shaft therein and revoluble therewith, said bucket having a reservoir movable therewith and opening into the shaft, a valve within the shaft for closing communication between the reservoir and mixing chamber, revoluble means above and movable with the bucket, a hoisting element disposed to engage and to actuate said revoluble means, mechanism for transmitting rotary motion from said means to the shaft, a valved actuating screw engaging the shaft, and means 115 120 125 130

for holding the screw against rotation during the rotation of the shaft.

6. Mixing apparatus comprising a yoke, revoluble means thereon, a hoisting element 5 adapted to engage and actuate said revoluble means, a tubular apertured shaft journaled within the yoke, a bucket revoluble therewith, mechanism for transmitting rotary motion from said revoluble means to the 10 shaft, a valve within the shaft, an actuating screw connected thereto and engaging the shaft, and means upon the yoke and screw for holding said screw against rotation, said bucket having a reservoir movable therewith 15 and opening into the shaft, said valve being disposed to close communication between the reservoir and shaft.

7. The combination with hoisting mechanism; of a bucket having a mixing chamber 20 and a reservoir, means operated by the hoist-

ing mechanism for mixing the contents of the bucket, and means carried by the bucket and operated by the hoisting mechanism for establishing communication between the reservoir and the bucket.

8. The combination with hoisting mechanism and a bucket having a reservoir and a mixing chamber; of revoluble mechanism operated by the hoisting mechanism for mixing the contents of the bucket, and means 30 operated by the hoisting mechanism and carried by the bucket for establishing communication between the bucket and reservoir.

In testimony that I claim the foregoing as my own, I have hereto affixed my signature 35 in the presence of two witnesses.
